UNITED STATES PATENT OFFICE.

WILLIAM B. HUGHES, OF CLEVELAND, OHIO.

GAS-PRODUCER.

971,272.

Specification of Letters Patent. Patented Sept. 27, 1910.

Application filed November 9, 1909. Serial No. 526,945.

To all whom it may concern:

Be it known that I, WILLIAM B. HUGHES, a citizen of the United States, residing at Cleveland, in the county of Cuyahoga and State of Ohio, have invented certain Improvements in Gas-Producers, of which the following is a specification.

My invention is a gas producer having improved means for sealing its bottom and removing the ashes therefrom.

The features characterizing my improvements are disclosed in the following description and the accompanying drawings in illustration thereof.

In the drawings, Figure 1 is a vertical sectional view of a gas producer embodying my improvements; Fig. 2 is a vertical sectional view taken at right angles to the section shown in Fig. 1, with modified details; 20 and Fig. 3 is a sectional view taken on the line 3—3 of Fig. 2.

The apparatus embodying my invention, as illustrated in the drawings, comprises the foundation 1 containing the central cavity 2 and the laterally extending pit 3. A circular sealing channel 4 has a bottom 4^a which rests upon the foundation, a circular inner wall or flange 4^b rising from the bottom 4^a around the top of the cavity 2, and a circular outer wall 4^c concentric with the wall 4^b. The channel 4 is provided with a removable bottom plate 4^d to prevent wear of the bottom 4^a by the ashes and the bottom has the aperture 4^e therethrough by which ashes are discharged from the channel to the pit 3. A hollow vertical column 5 provides a step bearing for the blast pipe 6 which is revolvble about a vertical axis and contains holes 6^a for admitting blast thereto from

40 the blow pipe 7. This latter pipe provides a passage through the foundation and the column to a space 5^a surrounding the holes, the blast passing thereby through the blast pipe and being diffused in the body 8 of the producer by the superposed deflectors 6^b and 6^c fixed to the top of the blast pipe. A circular bottom member 9 (serving as a supporting table, a grinder and a conveyer) is provided with a collar 9^a which is fixed on 50 the pipe 6, being engaged by the collar 6^d thereof. The body of the member 9 has the conical inner portion 9^b and the flat portion 9^c extending outwardly therefrom with the cylindrical part 9^d extending downwardly 55 around the part 4^b in the channel 4 to effect a seal. Helical ribs or blades 9^e, for break-

ing up and moving ashes, are formed on the top of the parts 9^b and 9^c, and wings or scrapers 9^f for moving the ashes are fixed to the part 9^d and extend outwardly therefrom in the channel 4. A cylindrical apron 9^g is fixed to and extends downwardly from the part 9^b into the circular channel 5^b formed on the top of the part 5 to hold water and provide a seal for preventing loss from the blast. Lugs 9^h are formed on the bottom of the part 9 and are adapted to be engaged by a pin 9ⁱ movable in a stationary bearing 9^j by means of a lever 9^k pivotally connected thereto and to the fulcrum 9^m.

The producer body 8 is provided with the conical ash hopper 8^a, concentric with the parts 6 and 9 which extend thereinto, and surrounding the hopper is a cylindrical apron 8^b fixed to the body 8, the apron having on the bottom thereof the exterior circular channel 8^c adapted for holding water to provide a seal for the bottom of the body. A cylindrical apron 10 is supported, removably, within the part 4^c and is provided at its top with the downwardly extending interior circular flange 10^a disposed in the channel 8^c to seal the bottom of the producer.

As shown in Fig. 1, the part 10 is provided with brackets 10^b which engage brackets 4^f on the part 4^c, by which the part 10 is held stationary. A poker or stirring bar 11 is movable through the bearing 4^g on the part 4^c and the bearing 10^c of the part 10 between the parts 8^a and 9^c to break up the ashes between the hopper 8^a and the bottom part 9. The body 8 is revolved by providing it with a circular rack 8^f and engaging the rack by a revolving pinion 8^g.

It will be understood that when the producer is revolved the weight and friction of the ashes which have passed from the part 8^a to the part 9 will revolve the latter, when free. When the bar 11 is inserted, the ashes between the revolving parts 8^a and 9 are broken up, the parts 9^c carrying the ashes outwardly to the channel 4 and the scrapers or wings 9^f carrying the ashes around the channel to the outlet 4^e, whence they are delivered to the pit 3 and removed therefrom in any suitable manner. If the ashes solidify so that they are not satisfactorily broken up with the part 9 revolving, it is held stationary by engaging the pin 9ⁱ with a lug 9^h while the part 8 revolves, the ribs 9^e still acting to pass the ashes outwardly to

the channel 4 whence they are removed on releasing the part 9.

As shown in Fig. 2, the part 10 has journaled on the exterior thereof the rollers or 5 wheels 10^d which are adapted to move on the circular track 4^e fixed within the part 4^c, and secured to the part 10 is a poker or stirring bar 12 which extends inwardly between the parts 8^a and 9^c to break up the 10 ashes. A rod 13 is movable through a bearing 4ⁱ in the part 4^c to engage a bracket 10^e on the part 10, whereby the latter can be held against movement or permitted to move.

15 The producer body 8 is provided with the brackets 8^d which carry wheels 8^e and the part 4^c carries the track 4ⁱ on which the wheels are adapted to move, the body being revolved by means of a circular rack 8^f fixed thereon and engaged by a revolving pinion 8^g.

Having described my invention, I claim:

1. A gas producer having a revoluble bottom with scrapers thereon, in combination 25 with a body revoluble independently of said bottom.

2. A gas producer having a channel, a revoluble body, means depending into said channel for sealing the bottom of said body, 30 a revoluble bottom member having sealing means depending into said channel, and one or more scrapers carried by said bottom member and acting in said channel.

3. A gas producer having a circular channel, a revoluble bottom having scrapers thereon movable in said channel, and a revoluble body above said bottom.

4. A gas producer having a revoluble body, an apron, sealing means connecting

said body and apron, a stationary channel 40 into which said apron depends, a revoluble bottom member adapted for discharging into said channel, and revoluble scrapers carried by said bottom member and acting in said channel.

45 5. A gas producer having a stationary channel, a revoluble body having a depending apron, means connected with said channel and apron for sealing the bottom of said body, a revoluble bottom member having an 50 apron depending into said channel, and one or more scrapers fixed to said member and acting in said channel.

6. A gas producer comprising a revoluble body having an apron with a circular channel, 55 a stationary channel, an apron having a member depending into said sealing channel and a member depending into said stationary channel, a revoluble bottom member beneath said body, and a stirring rod 60 connected with said second named apron, said rod extending between said body and bottom member.

7. A gas producer comprising a channel having a track thereon, a revoluble body 65 having wheels movable on said track, sealing means connecting said body and channel, a revoluble bottom member having a sealing flange and one or more scrapers in said channel, and a poker adapted to act 70 between said body and bottom member.

In witness whereof I have hereunto set my name this 28th day of October, 1909, in the presence of the subscribing witnesses.

WILLIAM B. HUGHES.
